BUILDING CONSTRUCTION

Maurice C. Rosenblatt, Philadelphia, Pa.

Application January 14, 1930, Serial No. 420,668

1 Claim. (Cl. 20—4)

This invention relates to building construction.

The invention pertains more particularly to ceiling constructions of buildings and to a modification of the present type of ceiling construction so as to present numerous advantages as will be pointed out but which particularly obviates all present forms of acoustical treatment or applications.

It will be clear, as the description proceeds, that there are many features of the present invention available or applicable to present types of acoustical treatments or applications, for which purpose it may be necessary to enlarge somewhat upon the acoustic problem generally. This should not be understood to minimize or alter the importance of the invention in the art of building constructions generally.

In the art of ceiling constructions according to universal previous practice the ceiling proper has been a heavy, rigid and expensive element suspended below in spaced relation to the supporting slab of the building. Owing to the presence of many factors which will be obvious to those skilled in the art, it is customary to provide a very appreciable space between the ceiling and the slab, which may vary between six and eighteen inches more or less. In the conventional ceiling construction, according to previous practice, a number of vertical hangers are suspended from the slab with their lower ends connected to a series of transverse girders in substantially grid-iron relation, to which a layer of expanded metal or other lath is affixed, which latter is the support for the three or more distinct coats of plaster which are subsequently applied to finish the ceiling. Owing to the weight of the plaster and lath, the hangers and girder elements must be of heavy construction which forms a large factor in the cost of the ceiling. Moreover, there is no way of "truing up" the ceiling other than by applying more plaster to bring a desired point up to the level.

It will be necessary to allude to present types of acoustic treatments in order to fully appreciate the advantages incident to the present invention. Acoustic treatments, in the forms presented heretofore always have been, at best, merely superficial impositions or applications. They have not heretofore been looked upon or considered as being or forming a fixed structural element or an intrinsic part of the main building structure itself. As an incident of their superficiality such treatments have been disadvantageous and inefficient on a great many points. This may be summarized, as regards the major disadvantages

at least, as follows. The superficial acoustic treatment is very expensive. As they cover and conceal a structural surface which has already previously been finished or at least substantially completed at appreciable cost, there is a further factor of high expense in this duplication of finish. Such superficial treatments being of an appreciable thickness materially reduce the ceiling height and the volume of the room to be treated. They add appreciable weight to structures which are already heavy. They are not adapted for making alterations, and the like, behind or in the treatments. The present treatments are so readily effected by age and by varying conditions such as settlement, shrinkage, humidity, as to be substantially temporary or at least impermanent. Of possibly greatest importance is their relative inefficiency from a sound absorbing view-point. This latter is despite the fact that the superficial acoustic treatments require costly sound absorbing means, and require expensive skilled labor to apply, but which, owing to the very nature of the treatment cannot provide enough sound absorbing material to be of very high absorbing value. For instance, in that type of treatment in which a layer of sound absorbing material, such as felt, or the like is pasted or otherwise supported upon the surface, there is a definite limit to the thickness of the felt that may be so applied, as, owing to its structural weakness and to the fact that the stress is transverse of the material, it tends to pull itself apart. Moreover, cements can only support a certain limited weight beyond which it is impractical and expensive to go. In other words, attempts to increase the efficiency of the modern superficial acoustic treatment requires the expenditure of greater and greater sums for the result. In the average superficial treatment then, relatively thin layers of absorbing material are used, which use militates against high sound absorbing efficiency.

The instant invention presents a construction so radically different from previous practices in acoustics as to be revolutionary, as it presents a ceiling construction having all of the necessary attributes of any ceiling construction, with an integral, built in, sound absorbing structure, which obviates all of the disadvantages of previous acoustic practices without added cost for the ceiling over the conventional construction presented heretofore and which, indeed, may even be cheaper than ordinary constructions.

Among the objects of this invention are; to provide a standardized building construction incorporating as an inherent part thereof a sound

absorbing structure; to provide an acoustic treatment of unprecedently high sound absorbing value; to provide a process for acoustic treatments generally which improves the value 5 of sound absorbing treatment; to provide a ceiling construction for buildings which incorporates an acoustic treatment of unprecedently high sound absorbing value without any increase in the cost of the ceiling construction; to provide a 10 building construction including means for improving the installation of a sound absorbing medium; to provide in acoustic treatments an improved outer exposed surface; to provide in building constructions a new ceiling finish; to 15 provide a decorated porous membrane for acoustic treatments without artificial or mechanical perforations in the surface; to provide an improved hanger for ceilings; to provide improvements in membranes of acoustic treatments such 20 that the natural porosity of the membrane can be utilized despite the applications of a decorating coat thereto; to provide a ceiling construction incorporating an acoustic treatment securing 100% absorption of the incident sound 25 energy; to provide an acoustic treatment in which the sound absorbing element is of far greater area than the exposed concealing element associated therewith; to provide standard building construction elements as the support 30 for an acoustically absorbent ceiling construction; to provide an acoustic treatment of such high sound absorbing efficiency that but a minimum of area of treatment is necessary to treat a given compartment of the building; to 35 provide a ceiling construction, incorporating sound absorbing structures, which is lighter in weight than the standard building construction; to provide an acoustic treatment in which the sound absorbing element may be of waste material and of the cheapest sort without adverse effect either in appearance or efficiency; to provide a ceiling construction incorporating an acoustic treatment of such simplicity that it may be installed by relatively unskilled labor and at 40 low cost; to provide a ceiling construction which can be levelled up by the operators without the customary wastage of plaster to secure the result; to provide a ceiling construction incorporating an acoustic treatment with which sound 45 damping means may be associated at low cost but with high efficiency; to provide an acoustic treatment which may be made fire-proof at little cost; to provide a membrane for an acoustic treatment in which the lines of the supporting 50 strips may be obliterated without decreasing the sound admitting and absorbing efficiency; to provide a ceiling construction incorporating an acoustic treatment which can be made sound proof as well as sound absorbing, and which 55 comprises a heat and cold insulator; to provide a ceiling construction providing for damping the vibration of pipes and ventilating ducts without interfering with the ceiling construction; to provide an improved hanger for ceilings to preclude 60 the transmission of vibrations between the ceiling and the slab; and many other objects and advantages as will become more apparent as the description proceeds.

In the accompanying drawings:

70 Fig. 1 represents a vertical section through a slab and wall with an illustrative form of ceiling according to this invention in operative association therewith,

Fig. 2 represents a similar section through a 75 slightly modified form of the invention disclos-

ing the association of sound proofing elements in the ceiling,

Fig. 3 represents a further modified form of ceiling installation in vertical section in which acoustic materials of fireproof construction may 5 be used,

Fig. 4 represents a fragmentary plan, partially in section of the supporting framework of the ceiling in an illustrative form,

Fig. 5 represents a plan and Fig. 6 represents 10 a section through a modification of the ceiling of this invention disclosing the combination of portions of a standard ceiling including a plaster or similar decorated ornamental surface, with a restricted but highly efficient area of sound admitting and absorbing exposed surface,

Fig. 7 represents a fragmentary elevation of the device for maintaining tension on a stretched portion of the ceiling,

Fig. 8 represents an elevation of a vibration 20 damping hanger such as may be used with this invention,

Fig. 9 represents a fragmentary vertical section on a highly magnified scale of the exposed surface of the ceiling according to one portion of 25 the invention, and

Figs. 10 and 11 represent fragmentary plans of the membrane disclosing the film forming layer of paint applied thereto and the pore openings formed by air pressure after blowing or sucking 30 the paint film from the membrane.

It will be understood that the ceiling of this invention is applicable to many different types of building construction and is not restricted to those providing a concrete slab as the ceiling 35 support, as this supporting floor may obviously be formed in any desired manner. Referring to Fig. 1, the slab 12 may terminate at or be intersected by a wall 13. A plurality of generally vertically extending hangers 14 are connected to the 40 slab to hang therebeneath in any number, order or size desired. The hangers 14 may be of any desired sort as to shape, weight, length or material according to the requirements of the particular installation. The hangers may be permanently attached to the under side of the slab, or may be attached as removable elements engaging permanent inserts mounted on the slab. At any rate there are a number of these hangers upon which the ceiling is supported. The hangers are illustrated for convenience as of angle iron, but the forms they may assume include channel iron, rods, straps and the like, fabricated in shops or on the job as may be indicated. They may comprise the isolating or vibration 55 damping hanger disclosed in Fig. 8. The feature of this hanger is that the strain on the hanger is transmitted through a wrapping of felt or other damping element. In an illustrative form as observed in Fig. 8, there is provided an outer 60 cylinder 15, which is hollow and is supported from the slab in any desired manner. The cylinder is provided with a vertical slot or slots 16, and at the lower open end has one or more bayonet joint slots 17. Mounted within the outer cylinder is a 65 smaller rod or tube 18, carrying a rigid cross pin 20 slidably disposed in the slots 16, and carrying in slidable relation toward its lower end a plug 21, having radial pins 22, arranged to engage in the bayonet joint slots 17. The inner rod or tube 70 has clearance from the outer cylinder and is embraced by a wrapping or tube of felt or other damping element 23, the upper end of which impinges upon a washer 24, and the lower end engaged by the plug 21. It will be clear that ac- 75

ording to the amount of damping material embraced between the washer 24 and plug 26 will be determined the effective length of the hanger. With the proper amount of damping material the 5 effective length of the assembled hanger will be as desired and the tensile strain on the smaller rod or tube will be transmitted through the felt or damping material to the outer suspended cylinder. A hanger as disclosed serves quite well 10 for general hanger purposes but is particularly available and desirable to preclude the transmission of vibrations between the ceiling and the slab. Obviously it is contemplated that where 15 conditions warrant a hanger of the characteristics of that shown in Fig. 8 may be used with the instant invention.

Regardless of the hanger used, there will be transverse supports, such as wires, rods, straps or channels, or the like, 25, extending horizontally 20 and connecting with desired hangers to brace the unit, and form supports for the later suspended absorbing material. There will be as many transverse rods and spaced such distances as are necessary under the circumstances of a 25 particular installation. It may be found best, for instance under certain conditions, to stagger the series of hangers so that the attachment of the transverse rods may be made to alternate pairs of hangers. In any case the transverse rods 30 will be connected to the hangers somewhere between the top and bottom of each hanger, and preferably at or just below the approximate centers of the hangers. Obviously the location of the transverse hangers will depend in certain 35 measure upon the amount of sound absorbing or damping material to be installed and the thickness of the entire ceiling. The lower terminals of the hangers will be connected to longitudinally extending strips or bars, such as channel bars 40 26, extending preferably perpendicularly to the transverse supports, and in vertical spaced relation thereto. The hanger and rod assembly will thus form a rigid and inflexible unit braced both ways, although the longitudinal and lateral bracings 45 will not be in the same plane substantially, but in vertically spaced planes, in the preferred form. Obviously the lowermost series of rods may be supplemented by additional rods to form a grid of extra rigidity, if this should be desirable. 50

It will be understood that this will be the framework which is erected to receive the remainder of the ceiling structure. It will be noted further, that if the hangers are of the type shown in Fig. 8, or of an equivalent construction, of 55 which many will occur to those skilled in the art, the lower faces of the channel bars or the like 26 may be levelled up into exactly the level desired, by making adjustments of certain hangers. Such adjustments will also be made to cause 60 the ceiling to adhere to predetermined heights so that these heights may be secured without the deviations formerly inevitable with ceiling constructions.

The transverse supports 25 are arranged to be 65 disposed in the waste space of the ceiling, that is in space that is usually available in any ceiling construction but which heretofore has represented a true economic waste. With the open framework as described, and substantially as 70 shown in Fig. 4, for instance, sound absorbent material is inserted and draped or hung in loops over the series of transverse supports 25, as shown in Figs. 1, 2, and 3. The sound absorbent material 27, (Fig. 1) is simply fed endwise over 75 the several transverse bars, and is supported

easily and without strain. It is usually unnecessary even to attach the material to the bars, as it merely rests upon them and is not subject to displacing stresses. Obviously, in the preferred form at least, the material will be pliable and 5 susceptible to bending so that a great area of it may be inserted in the ceiling by forming it in loops or the like, as shown. It may take many forms, such as reinforced felts, fire-proof felts, quilts, ground cork, mineral wool, and the like. 10 In the various felts that are available it is of interest to note that owing to the manner of forming the felts, the fibers of the felt lie in substantial planes parallel with the faces of the finished felt, and although slightly admixed, are of such 15 construction that lateral stresses against the grain may cause the felt to separate into strata, but the tensile strength of the felt is much greater. It is of importance to note that according to this invention the only stress on the felt 20 (when felt is used) comes from the weight of the loop suspended between the two transverse bars, and this strain is almost entirely tensile. This is in contrast to the previously acoustic practices where the felt is pasted to a surface so 25 that gravity exerts a pull transversely of the felt with undesirable effects. In the case of the loose unfabricated sound absorbing materials such as the ground cork, mineral wool, and the like, there is provided a looped support such as a wire 30 screen or the like, as at 28, in Fig. 3, upon which the granular or loose material 30 is piled to a depth that is suitable. If desired the ends of the looped strip of sound absorbing material may be attached to the end transverse rod in any desired 35 manner (not shown). It is to be noted that the looped material is to be as thick as desired, and may be comprised of several different layers. Its thickness is only limited by the distance that the ceiling construction is suspended below the 40 slab or floor above. It is to be observed that by providing the looped material as disclosed, a quantity of material may be introduced which in area is far greater than its reflected area. To secure the introduction of more material in the 45 given ceiling area it is but necessary, obviously, to increase the number or length of the loops. It is quite easy to secure an area of sound absorbent material that is twice the area of the effective ceiling area, or an even higher ratio may 50 be attained, according to conditions. For this purpose it is contemplated that wires or the like, (not shown) may be inserted into the rigid ceiling framework between the transverse bars as auxiliary loop supports. In any case it is preferable that there be a number of loops so that 55 the effective sound absorbing area of the material is appreciably increased so that the unit efficiency of the material (the reflected unit) is multiplied several times. This is of far reaching 60 importance as it enables the absorbing material to attain an unprecedented sound absorbing efficiency. For instance, a felt of one inch thickness may in its flat condition absorb as high as 65 50% of incident sound, but when installed as disclosed herein will easily absorb 80% of the incident sound, per unit of reflected area and without difficulty, by providing sufficient area of absorbing material the treatment may be so increased in efficiency as to secure 100% absorption 70 of incident sound, which is a complete absorption as compared with the absorption standard, which is known to be the open window. The main function of the construction so far described is to secure a maximum of sound ab- 75

sorbing area with a minimum of cost or trouble, but obviously the same effect may be secured in other ways, as, instead of looping the sound absorbing material over the transverse bars, as shown, the material may be hung from the transverse bars or from other supporting elements, in the form of a profusion of vertical strips for instance, (not shown).

It is pointed out that whereas with the present superficial imposition constituting the acoustic treatment, the sound absorbing elements used in such superficial applications must have good surface texture, uniformity of thickness, homogeneity of structure, and the like, which requirements contribute materially to the high cost of the treatment, the sound absorbing elements available for the instant construction can be relatively crude, unrefined and therefore relatively inexpensive. Indeed the materials used may even include inexpensive waste material.

The problem of sound proofing designed to preclude the transmission of vibrations from one compartment of a building to another, or into the structure itself, according to previous practice, was a separate consideration and had to be accomplished separately from the acoustical application. In the instant invention sound proofing may be combined with sound absorbing very simply and economically, as shown in Fig. 2, in which with the identical assembly already described, and with the loops of acoustic or sound absorbing material 27 hung upon the transverse supports 25, layers 31 of damping material, such as a layer or combination of layers of artificial fiber board, are laid upon the high parts of the loop and upon which they permanently rest. A refracting layer of material of different density from layer 31, as layer 32 may be laid upon the fiber board 31 and if desired still another layer 33 of damping material of any desired sort as 33 may be superimposed on the refracting layer 32. These sound damping stratifications need not be fastened in position but simply laid upon the peaks of the loops or other suitable supports. While it is desirable that the damping layer 31 be of a relatively stiff material, damping layers 32 and 33 may be relatively soft and pliable if desired.

It will be understood that the lower portion of the ceiling may comprise any desired exposed decorated or undecorated surface so long as a portion at least, of sound waves incident upon the exposed surface may pass into the ceiling proper to impinge against the surface of the sound absorbing material. In its broadest aspect therefore, it may suffice to note that the ceiling is finished with a more or less porous surface element 34.

It will be obvious to those skilled in the art that the exposed surface 34 may assume many forms, and be of many materials, but in the preferred form is preferably comprised of a stretched and taut porous membrane 35, to which an exposed finish element 36 is pasted. In order to mount the finish members in position there are provided a number of furring strips 37 (Fig. 1) which may be supported in the plane of the bottom reinforcing bars 26, or, may be attached to the under surface of said bars as shown in Figs. 1, 2, 3, and 4. The furring strips may be attached in any desired manner whatever to the channel bars 26 and in the form disclosed in Fig. 1 are permanently secured in a fixed position. A membrane 35 may be attached to one furring strip extending transversely across the ceiling in a substantially hori-

zontal plane and passing around the end of the adjacent furring strip and may be affixed thereto in any desired manner. A complementary furring strip 38 may be attached to the furring strip 37 about the corner of which the next expanse 5 may be pulled. In Fig. 1, furring strip 37 is disclosed as supporting a lug 40, the outer end of which carries a spring 41 arranged to be engaged in any desired way with the end of the membrane 35 as at 42. The purpose of this spring is to 10 maintain the tension of the stretched membrane, as will be clear. In Fig. 2 a slightly modified form of attaching device is disclosed in that a plate 43 having serrations or teeth 44 is mounted on the side of the furring strip with the end of membrane 15 hooked upon the teeth of the plate. In Fig. 7 a further modification is disclosed in which the tension on the stretched membrane is maintained by spring pressure by providing the furring strips 45 with bolts or pins 46 engaging in longitudinal slots 20 47 in the channel bar 26 so that the furring strips may have a limited movement. Tension on the membrane is secured by providing some such device as a bowed spring element 48, arranged to seat upon and urge the respective furring strips 25 45 apart. It will be understood that the first furring strip is located by a wall so that tension of the spring in one direction is absorbed by such wall, but wherein succeeding furring strips are urged away from said wall to maintain the tension on the membrane. It will be apparent that with a device as disclosed in Fig. 7 it will be possible to finish the last panel by compressing the spring 48, while the furring strip is spaced from the wall as by blocks (not shown) after the membrane is attached thereto, then by removing the blocks holding said furring strips, to permit the furring strip to move and impart tension to the membrane in such last panel.

The invention contemplates important features 40 applicable generally to the art of acoustics, and one of these features is the method by which a decorative finish is applied to the finishing members substantially without impairment of the natural porosity of the member. One of the factors militating against the use and success or efficiency of fabric membranes in the past, has been the fact that although in their natural highly porous condition they have been very efficient, yet the application of a decorative finish 50 such as paint, has created a film which is not only reflective of incident sound, but which, through closing the pores of the material, has rendered it of low acoustic value. The ceiling element 35 is preferably open mesh fabric such as burlap, aberdeen cloth, and the like, or it may be asbestos cloth or perforated reenforced asbestos paper, or a wire mesh, or similar material including a rigid apertured sheet such as sheet iron and the like. It is probable that burlap will, in many cases, be 60 the preferred material and this preferably is bleached before application. The burlap or other ceiling element receives and carries the first coat of paint. This may be applied in any desired manner as by brush or by spray, and the paint 65 may be of any desired material or consistency. If desired it may be one of the standard fireproofing paints to add to the fireproofing qualities of the structure. In one phase of the invention and in order to prevent the formation of a paint film 70 which would cover the pores of the membrane, it is contemplated that an air or spray gun may be used projecting finely atomized paint particles toward the surface of the membrane, the arrangement being such that the particles of paint im- 75

pinged upon strands of the fabric will be deposited on said strands, but that the particles passing through the pores will be blown completely through the membrane and possibly deposited upon the loops of absorbent material suspended above the membrane. The spray gun may be so used that the pressure applying the paint is sufficiently great as to prevent the formation of the film, if desired. In either of these cases, however, the important effect is achieved of depositing color or pigment upon the porous material without clogging up or covering over the pores.

Immediately after the paint is applied and while it is still wet enough to be so treated, the surplus material, if any, is blown out of the mesh so as to maintain its original porous condition. This may be accomplished in a number of ways as by a simple motor driven blower or by vacuum equipment. The ceiling element 35 may be treated with dry pigment to create the desired color before its installation in the ceiling, or it may previously or subsequently be stained or dyed.

In Fig. 9, the ceiling element 35 is disclosed on a highly magnified scale and with the paint 50 attaching to the meshes of the fabric in isolated discontinuous points or area so that the porosity of the element 35 is substantially maintained. This method of procedure in the finishing of an acoustic membrane so as to secure hiding power without the formation of a film, is important.

The finish element 36, which, preferably comprises a fabric of possibly finer mesh than the ceiling element 35, and may be of any of the materials available for the ceiling element, is pasted or cemented to the ceiling element 35, preferably after the ceiling element is stretched in position and directly following the pasting operation and while the paste is still moist enough to work, surplus paste or cement is blown or sucked out of the meshes in the same manner as previously described. The finish element 36 may be applied in a continuous layer, with joints abutted together or blinded, or it may be applied to form any desired design or relief. The second coat of paint, or the like, is applied to the finish element and the surplus moist material is withdrawn as before to maintain the porosity of the finished material. In this manner therefore, the painting of the treatment does not detract from its sound absorbing effect, and it may therefore be repainted and cleaned repeatedly at will in the same manner, without detrimental effect. It is of interest to note that although there may be two coats of paint applied, yet owing to the fact that they are applied to superimposed layers, the layers of paint are slightly separated and owing to the staggered effect available with fabrics of

different mesh, the hiding power of the two coats of paint is substantially utilized.

In many cases it may be desirable to provide decorated plaster panels, or the like, in the ceiling which with present superficial acoustic treatments would be impossible. Owing to the extraordinarily high sound absorbing efficiency of the sound absorbing material arranged as disclosed in the invention, as an incident of the fact that sound waves travel and may impinge upon the absorbing material in an infinite number of angles, it is possible to provide an effective acoustic area of ceiling, which, according to all previous standards would be inadequate for acoustic purposes, but which lead to or open upon areas of absorbing material of such great absorbing power, as to render the unit absorption for the ceiling still of unprecedentedly high efficiency. For instance, in the disclosure of Figs. 5 and 6, the ceiling is provided with moldings, beams and the like 51, 52, 53, and 54 connected by an expanse of plastered ceiling, as 55, which may be built up and supported upon reinforced hangers 56 supporting metal lath 57 and the plaster layers and the moldings. In an area defined by molding 52, 53 and 54 there may be acoustic panels, respectively, 58, 60 and 61, comprising stretched membranes or other porous exposed material so as to impart a finish to the acoustic panels but to provide passage ways for the sound waves leading to the many loops of absorbent material suspended within the ceiling above the ceiling finish as disclosed in Fig. 6. With the panel effect disclosed in Figs. 5 and 6, the available acoustic area of the ceiling may form as low as 30% of the entire area, but by providing enough of the sound absorbent material over the entire area approximately, and by maintaining the porosity of the finish in the acoustic panels, such a high degree of absorption may be had as 40 to give a unit absorption for each panel of approximately 100%.

Obviously the invention disclosed herein will be subject to many modifications, as will be clear to those skilled in the art, and it is desired that all such shall be construed as within the scope of the invention as recited in the appended claim.

I claim as my invention:

In a ceiling construction, a supporting slab, an area of ceiling material including a restricted area of porous ceiling material spaced from the slab and with the porous area of smaller area than said slab, and sound absorbent material arranged between the slab and said ceiling material of far greater area than either the reflected slab area or the porous ceiling area.

MAURICE C. ROSENBLATT.
